SUN-BLIND

Arthur Linley Jones, Roundhay, Leeds, and Donald Kilbey Smith, Chingford, England

Application November 8, 1937, Serial No. 173,360
In Great Britain November 13, 1936

6 Claims. (Cl. 156—44)

This invention relates to improvements in sun blinds and the like and more particularly to sun blinds for shop fronts.

In the normal construction of a shop blind it is usual to lower and raise the blind by means of a pole, which action requires some considerable effort on the part of the operator, often making it a difficult matter for a female shop assistant to raise or lower the blind apart from the fact that the operator has to go outside the shop into what may be inclement weather.

One object of the present invention is to provide a blind structure which may be raised and lowered from within the shop without requiring heavy manual exertion on the part of the operator.

Another object of the invention is to provide a blind structure which may be lowered and raised wholly or partially by gravity.

The above and other objects of the invention will become apparent from the following description.

In order that the invention may be clearly understood and readily carried into effect, two constructions thereof are hereinafter more fully described with reference to the accompanying drawings which are given by way of example only and not of limitation.

In these drawings:—

Figure 1 is a side sectional elevation of a shop front incorporating one construction of blind mechanism.

Figure 2 is a plan view of the blind mechanism showing the blind extended.

Figure 3 is a longitudinal section through the blind roller.

Figure 4 is a section taken on the line IV—IV of Figure 2 shown on an enlarged scale, and

Figure 5 is a similar view taken on the line V—V of Figure 2.

Figure 6 is an end view of a modified construction, and

Figure 7 is a front section view of one end thereof.

Referring firstly to Figures 1 to 5 of the drawings, the blind 1 is attached at one end to a blind roller 2 and at the other end to a lath 3 supported by a pair of hinged arms 4, 4' and 5, 5'. The arms 4, 5 are mutually pivoted and pivotally connected both to the lath 3 and to a cross-bar 6 journalled in brackets 7, 8 mounted on the back of the blind-box. Adjacent each end the cross-bar 6 carries fast therewith toothed segments 9 and 10 respectively.

Adjacent the bracket 7 is a second bracket 11.

A shaft 12 journalled in the brackets 7 and 11 carries a toothed wheel 13 in mesh with the teeth of the segment 9 and also a further toothed wheel 14. A similar auxiliary bracket 15 is mounted adjacent the bracket 8 and a shaft 16 similar to the shaft 12 is journalled in those brackets. Toothed wheels 17, 18, similar to the toothed wheels 13, 14 are mounted on the shaft 16.

A transverse shaft 19 is journalled in the four brackets 11, 7, 8, 15, and fast thereon are a pair of similar toothed wheels 20, 21 meshing respectively with the toothed wheels 14 and 18. Also, fast on the shaft 19 is a toothed wheel 22 meshing with a toothed wheel 23 on a shaft 24 also journalled in the brackets 8, 15, to form a chain of reducing gears. The toothed wheel 23 meshes with a toothed wheel 25 having a hollow boss 26 which extends loosely into the flanged end 2' of the blind roller 2.

A bevel toothed wheel 27 fast on one end of the shaft 19, meshes with a bevel toothed wheel 28 on a shaft 29 which is adapted to be rotated through the bevel gears 30, 31 by means of a crank handle 32. Any other convenient mechanism may, however, be employed to impart rotation to the shaft 19.

The other end of the blind roller 2 is a tight fit on a flanged element 33 on the flange of which are teeth 34 engaging teeth 35 on a plate 36. Both the plate 36 and toothed wheel 25 are free to rotate on the spindle 37 which is secured to the brackets 7 and 8.

The spindle 37 has a threaded portion 38 on which are mounted a pair of nuts 39, 40. The nut 39 may rotate independently of the boss 26 while the nut 40 is adapted to rotate therewith, although it is free to move with respect thereto axially along the spindle. The nut 39 has a projection 39' adapted to engage a corresponding projection 40' on the nut 40. To the nut 39 is made fast one end of a coil spring 41, the other end of which is secured to the element 33. To regulate the tension of the spring 41, a nut 42 on the threaded portion 43 of the spindle 37 is slackened off and the plate 36 is displaced to remove its teeth 35 out of engagement with the teeth 34 of the element 33, whereupon the latter is rotated to impart the desired tension to the spring 41 when the nut 42 is retightened to bring about re-engagement of the teeth 34, 35.

The operation of the mechanism is as follows:—

The crank handle 32 is rotated to impart rotation to the shaft 19 thereby rotating the toothed wheels 20, 21 and with them the toothed wheels 14 and 18. Thus, the shafts 12 and 16 are ro-

tated and thereby the toothed wheels 13 and 17 to displace the segments 9 and 10. At the time the segments are brought to the position shown in Figures 4 and 5, the arms 4, 4' and 5, 5' are inclined downwardly and the weight of the lath 3 tends to cause them to extend due to gravity. During the rotation of the shaft 16 the toothed wheel 18 is rotated and thereby the toothed wheel 25 through the reducing gears 21, 22 and 23. Rotation of the toothed wheel 25, rotates the nut 40, due to its engagement with boss 26, and by its engagement with the threads 38 causes it to move towards the right as seen in Figure 3. The projection 40' leaves the projection 39' whereupon the blind roller 2 is free to rotate. As the blind runs out, the rotation of the element 33 increases the tension of the spring 41, the effect of which is to cause rotation of the nut 39 and cause it also to move axially of the spindle towards the right as seen in Figure 3. When the projection 39' re-engages the projection 40' further movement is arrested whilst the spring 41 is still under tension thus keeping the blind taut.

To retract the blind, the crank handle is rotated in the opposite direction when the arms 4, 4' and 5, 5' are elevated to an upwardly inclined position, as shown in chain line in Figure 1, when they tend to collapse due to gravity. The rotation of the toothed wheel 25 in the opposite direction causes the nut 40 to move axially towards the left and with it the nut 39 due to the engagement of the projections 39', 40'. The tension of the spring 41 is thereby increased and this causes rotation of the blind roller to wind on the blind, the increase in tension being discounted by the movement of the roller.

Limit stops or hydraulic checks of known construction may be employed to restrict the opening of the arms 4, 4' and 5, 5'.

In a modified construction shown in Figures 6 and 7, the blind box 50 is mounted for bodily rotation, about pivots 51, within a fixed casing 52. The blind lath 53 is connected by arm 54 to lattice or lazy-tong arms 55 carried by depending brackets 56 mounted on the front of the movable blind box 50. The blind extends from the lath 53 over a roller 57 loosely mounted on the bosses 58, 59 of bearing members 60, 61 extending through the end walls 50a, 50b of the movable blind box 50.

On a stub shaft 62 are mounted gear wheels 63, 64 adapted for mutual rotation. The toothed wheel 64 meshes with a toothed ring 65 of a ratchet or one-way device 66 on the member 67. This member 67 has an extension 68 of square section upon which is mounted a nut 69 having a peripheral thread engaging internal teeth on the boss 58 of the members 60. A spring 70 is made fast to the blind roller 57 and to the nut 69.

The lath 53 is maintained in close position by a spring-urged catch 71 taking over the edge of the front wall of the blind box 50. On the inside of that wall is mounted a spring-urged sliding member 72, whilst a similar member 73 is mounted on the bottom of the fixed casing. The adjacent ends of the members 73, 72 are chamfered or sloped such that when the element 73 is displaced to the left, as seen in Figure 6, it moves the member 72 upwardly to raise the catch 71 clear of the edge of the front wall of the blind box. When this catch 71 is so released, the weight of the lath and the slight downward inclination of the lattice or lazy-tong arms 55 is such that the lattice or lazy-tong arms extend.

As the blind 1 is reeled off the roller 57, the tension of the spring 70 is increased thereby causing rotation of the nut 69 and with it the parts 68, 67, 65, 64. During this rotation, due to the engagement of the nut 69 with the teeth on the boss 58, the nut 69 moves towards the right as seen in Figure 7. The arrangement is such that the nut 69 strikes against the member 70 and is arrested thereby just before the blind is completely unwound whereby tension is maintained on the spring which keeps the blind taut.

The element 73 is moved by a spring-urged rod 74 connected to bell crank lever 75 to which is connected a depending rod 76 disposed within the shop which may be operated manually to rock the bell crank lever to displace the member 73 and element 72 to release the catch 71, in order to lower the blind.

The ram 77 of a hydraulic cylinder 78 is pivotally connected to the blind box 50 and when it is desired to retract the blind, fluid is introduced into the hydraulic cylinder by a suitable control to cause movement of the ram which, in turn, rocks the blind box 50 about the pivots 51 to raise the lattice or lazy-tong arms 55 to a generally upwardly inclined position when they tend to retract due to gravity.

As the blind box 50 swings about the pivots 51, the toothed wheel 63 meshes with a toothed rack 79 secured to the end wall of the fixed casing. This engagement causes rotation of the toothed wheel 63 and with it rotation of the toothed wheel 64, in an anti-clockwise direction. This toothed wheel 64 rotates the toothed ring 65 and by engagement of the ratchet 66 rotates the member 67 in a clockwise direction. This causes reverse travel of the nut 69 which increases the tension of the spring 70. The increase in tension of the spring brings about rotation of the roller 57 to cause winding on of the blind 1.

When the blind is fully rolled up and the lath has abutted the front of the blind box 50 with the catch 71 engaged, the fluid is allowed to escape from the hydraulic cylinder and the blind box allowed to return to the normal position shown in Figure 6. During this reverse movement the toothed wheels 63, 64 are rotated in clockwise direction and likewise the toothed wheel 64 which, however, idles with respect to the members 67 so that the blind is not payed out.

The invention is not limited to the embodiments hereinbefore described by way of example and various modifications or alterations may be made therein without departing from the spirit or scope of the invention as defined by the appended claims.

We claim:

1. A sun blind, including a lath, supporting arms therefor, and means adapted to rock said arms to a downwardly inclined position to cause extension thereof and to elevate said arms to an upwardly inclined position to cause retraction thereof due to gravity.

2. In a sun blind, a blind roller, extension arms and a lath supported thereby, means operable to incline said arms in a generally downward direction to cause the same to extend by gravity and operable to incline said arms into a generally upwardly inclined position to cause retraction of the arms also due to gravity.

3. In a sun blind, a lath, pivoted arms supporting said lath, means on said arms for displacing the same about a horizontal axis into a generally downward direction to cause the same to extend by gravity or into a generally upwardly inclined

position to cause retraction of the arms also due to gravity, and means operable to displace said means.

4. In a blind construction, a lath, hinged arms supporting said lath, toothed segments on the ends of said arms, mutually rotated toothed wheels meshing with said segments and means for rotating said wheels to rock said segments to incline said arms into a generally downward direction to cause them to open by gravity or to incline them into a generally upward direction to cause them to retract also by gravity.

5. In a blind structure, a lath, supporting arms therefor, a transverse bar supporting said arms, toothed segments on said bar, toothed wheels

meshing with said toothed segments and means for rotating said toothed wheels to cause rotation of the segments about the axis of the bar to incline said arms into a generally downward direction to cause them to open by gravity or to incline them into a generally upward direction to cause them to retract also by gravity.

6. A sun blind, including a lath, a pivoted blind box, hinged arms connecting said lath and said blind box, catch means operable to release said lath to extend said arms by gravity, and means for rotating said blind to elevate said lath and arms to cause retraction of the latter.

ARTHUR LINLEY JONES.
